WITNESSES:

UNITED STATES PATENT OFFICE.

ALEXANDER C. MIKANOVICH, OF CLEVELAND, OHIO.

DIRIGIBLE.

1,395,051.

Specification of Letters Patent.

Patented Oct. 25, 1921.

Application filed November 23, 1920. Serial No. 425,992.

To all whom it may concern:

Be it known that I, ALEXANDER C. MIKANOVICH, a citizen of Hungary, residing at Cleveland, in the county of Cuyahoga and State of Ohio, have invented new and useful Improvements in Dirigibles, of which the following is a specification.

This invention relates to dirigibles, and has particular reference to the passenger carrying type, the invention providing a construction possessing maximum strength, and wherein the passenger carrier is effectively and rigidly supported to insure safety.

15 The nature and advantages of the invention will be better understood when the following detail description is read in connection with the accompanying drawings, the invention residing in the combination, construction and arrangement of parts as claimed.

20 In the drawings forming part of this application like numerals of reference indicate the similar parts in the several views and wherein:

Figure 1 is a side elevation of the dirigible constructed in accordance with my invention.

Fig. 2 is a bottom plan view.

30 Fig. 3 is an enlarged transverse sectional view.

Fig. 4 is an enlarged fragmentary detail view of one of the rims.

Fig. 5 is a fragmentary view in elevation 35 taken at right-angles to Fig. 4.

Fig. 6 is an enlarged fragmentary view showing the connection between the rims of the passenger carrier.

In accordance with the present invention 40 the dirigible embodies a plurality of substantially rim-like members which are suitably spaced apart as shown in Fig. 1. Each rim-like member comprises a hub 10 from which radiates spokes 11, each of the latter 45 including two sections which are suitably connected together by means of a turn buckle or the like 12. Arranged within each hub are opposed bracing elements 13 and 14 respectively which have arranged between them the connecting rod 15 which holds the rim-like members suitably spaced apart. Each rim-like member is made up of two frames or sections A and B respectively, while each section comprises a plurality of units 16, the sections may of course 55 be made from any suitable material, al-

though the units 16 are constructed of metal and preferably of angle-iron formation as shown. The units 16 of section A intersect the corresponding units of the section B, 60 and are bolted or otherwise suitably secured at their points of intersection such as at 17. The adjacent ends of the respective units of each section overlap and are provided with squared openings through which pass 65 tubes 18 which are preferably of rectangular formation in cross section. The spokes 11 radiate from the hub 10 of each rim-like member and are connected to the units of the section B at the point of connection between the adjacent extremities thereof, and also connected with the said units at a point approximately midway between the ends. Manifestly, by reason of the relative arrangement of the units 16 of the respective 75 sections A and B a plurality of triangles are outlined by the intermediate portion of the units of section A of the adjacent extremities of the units of section B, which construction affords the dirigible maximum 80 strength and rigidity. The construction just described is of course concealed by the flexible covering 19, while it is to be understood that gas bags (not shown) are to be arranged between the rim-like members. 85 Any number of rim-like members may be employed, this of course depending upon the size of the dirigible.

The rim-like members have their ends spaced apart adjacent the bottom of the dirigible, these ends connected together by horizontally disposed members 20 which are of preferably angle formation. These members 20 constitute what I term a base for the structure, the units 16 of the sections of the 95 rim being connected to the base as at 21. It is from this base that the passenger carrier is suspended, the carrier being made up of a plurality of frame like members 22 and 23 which are disposed relatively to provide 100 a hall 24 at the opposite sides of which are cabins 25. The carrier in its entirety is suitably connected to the base by means of the supporting elements 26, while the base of the structure of the members 20 are connected with the adjacent spokes 11 radiating from the hub 10. As shown in Fig. 1 the cabins are provided with windows 27 while the under side of the dirigible is equipped with door openings 28 through which passengers enter and leave the cabins. Arranged beneath the passenger carrier is a

gas supply tank 29 while carried by the carrier at the forward and rearward ends thereof are motors 30.

It is quite obvious from the foregoing description that I have devised a construction of a passenger carrying dirigible that possesses maximum strength and rigidity to insure safety, and while I have shown and described what I consider the preferred embodiment of the invention I desire to have it understood that I do not limit myself to what is herein shown, and that such changes may be resorted to when desired, as fall within the scope of what is claimed.

15 What I claim is:—

1. A dirigible including a plurality of rim-like members spaced apart, each member comprising sections made up of a plurality of angularly disposed units, the units 20 of one section intersecting the corresponding units of the other section and secured thereto, parallel elements connecting the adjacent extremities of the units of each section, a hub, adjustable elements radiating 25 from the hub and connected with the sections of each member, and a flexible covering for said structure, and a passenger carrier supported by said members.
2. A dirigible including a plurality of 30 rim-like members spaced apart, each member including sections made up of angularly disposed units connected together, a hub for each member, and spokes radiating from the hub and connected with the sections of said member, opposed bracing elements carried in each hub, a connecting rod passed through the hubs of said members and arranged between said bracing ele-

ments, a passenger carrier supported by said members, and a flexible covering for said 40 structure.

3. A dirigible including a plurality of rim-like members spaced apart, means for holding said members spaced, each member comprising sections made up of angularly disposed units, a hub, and spokes radiating from the hub and connected with said units, the units of one section intersecting the corresponding units of the other section and secured thereto, parallel rods 45 connecting the adjacent terminals of each section, a series of triangles, horizontally disposed elements connecting the terminals of said members and constituting a base, a passenger carrier and supported by said 50 base, and a flexible covering for said structure.

4. A dirigible including a plurality of rim-like members spaced apart, means for holding said members spaced, each member 60 comprising sections made up of angularly disposed units, parallel rods connecting the adjacent terminals of the units of each section, the units of one section intersecting the corresponding units of the other section and 65 secured thereto, the adjacent terminals of the units of one section being disposed above and in a point midway between the terminals of the adjacent units of the other section, a hub for each member, spokes radiating 70 from the hub and connecting the units of said sections, the passenger carrier supported by said members, and a flexible covering for said structure.

In testimony whereof I affix my signature. 75
ALEXANDER C. MIKANOVICH.
